REFRIGERATING APPARATUS

Nicholas J. Bohn, Detroit, Mich., assignor, by
mesne assignments, to Nash-Kelvinator Cor-
poration, Detroit, Mich., a corporation of Mary-
land

Application April 18, 1936, Serial No. 75,165

1 Claim. (Cl. 62—89)

This invention relates to refrigerating apparatus, and more particularly to refrigerating apparatus of the household type.

One of the objects of my invention is to provide an improved refrigerating apparatus of the household type wherein provisions are made for storing large and small food articles to be refrigerated, with the small articles being disposed on shelves fixed to stationary wall members near the front part of the cabinet so that same are readily accessible upon opening of the refrigerator door.

Another object of my invention is to provide a refrigerator of the so-called unit type with a vertical wall member which cooperates with other walls to provide the space for the refrigerant condensing element in the upper rear part of the cabinet and at the same time the vertical wall is spaced a short distance from the front part of the cabinet so as to provide an auxiliary food storage compartment for small articles immediately adjacent the door opening.

Other objects and advantages will be apparent from the following description and accompanying drawing, wherein a preferred form of the present invention is clearly shown.

In the drawing:

Fig. 1 is a view in elevation, partly broken away, showing refrigerating apparatus embodying my invention;

Fig. 2 is a view taken along the line 2—2 of Fig. 1;

Fig. 3 is a fragmentary view in elevation of a modified form of refrigerating apparatus embodying features of my invention; and

Fig. 4 is a vertical view in cross section of the refrigerating apparatus shown in Fig. 3.

In refrigerators of the household type, difficulty has been found in providing a readily accessible place for storing small food articles, such as eggs, butter, oranges and the like. In making provision for the storage of such small articles, it has heretofore been the practice to store same in small storage shelves carried by the refrigerator door. However, this condition had several disadvantages, such as the insulation of the door had to be reduced, thereby increasing the heat transfer characteristics into the cabinet, and another disadvantage was that opening of the door created noise and possible breakage of the small articles. By my invention I overcome these difficulties, by providing a relatively small food storage compartment as an auxiliary compartment associated with the main food storage compartment, and in the relatively small food stor-

age compartment I have made provision for supporting these small food articles. Preferably, the shallow food storage compartment is located in the upper forward part of the cabinet so that the small articles are readily accessible upon opening the refrigerator door.

Referring to the drawing, the numeral 20 designates, in general, a refrigerator cabinet embodying features of my invention. The cabinet includes vertical walls 21, lower horizontal 10 wall 22, upper horizontal wall 24 and an intermediate horizontal wall 26 which extends forwardly from the rear vertical wall 21 to an upright vertically disposed wall member 28. These walls cooperate to provide a main food storage 15 compartment 30 and a relatively shallow depth auxiliary food compartment 32. The front part of the cabinet is provided with an opening 34 closed by door 35. Shelves 38, of the well known open work type, are provided in the main food 20 compartment for supporting relatively large food articles. Within the auxiliary food storage compartment 32 there are provided open work basket type shelves 40 for supporting small articles, such as eggs, butter, oranges and the like. The 25 shelves 40 may be attached to wall 28 by any suitable means.

The air in compartments 30 and 32 is cooled by a refrigerant evaporating element 45 which is supported by wall 26. A refrigerant condensing 30 element 47 is operatively connected with the evaporating element 45 and is supported on the opposite side of wall 26. The compartment 32 will be maintained at a higher temperature than compartment 30, due to the fact that cold air descends and the evaporator 45 is located below compartment 32.

The apparatus shown in Figs. 3 and 4 includes a cabinet 60, evaporator 62, condensing element 63 which correspond in all respects to cabinet 20, 40 evaporator 45 and condensing element 47, respectively, with the exception of the door 65 of cabinet 60. Door 65 is provided to close opening 67. In this embodiment of my invention, the door 65 is provided with an inner pan 70 extending into 45 opening 67. This inner pan extends from the lower part of door upwardly but terminates a considerable distance below the top of door so as to provide additional room for shelves 72 in auxiliary compartment 75.

From the foregoing, it will readily be apparent that I have made provisions for the storage of small articles in a space readily accessible upon opening of the refrigerator door and at a very convenient location in the refrigerator, and the 55

supporting shelves are rigidly secured to a fixed part of the cabinet.

Although only a preferred form of the invention has been illustrated, and that form described in detail, it will be apparent to those skilled in the art that various modifications may be made therein without departing from the spirit of the invention or from the scope of the appended claim.

10 I claim:

Refrigerating apparatus comprising a cabinet having a vertical wall and a horizontal wall arranged to cooperate with other walls to provide a main food storage compartment and a relatively 15 small food storage compartment above the main

food storage compartment, a refrigerant condensing element carried on one side of said horizontal wall, a refrigerant evaporating element carried below said horizontal wall so as to cool said main food compartment to a considerably lower temperature than said relatively small food compartment and being operatively connected with said condensing element, open-work shelves carried by said vertical wall and extending substantially from one side of the cabinet to the other for receiving 10 small food articles, said cabinet being provided with an opening for gaining access to said compartments, and closure means for said opening.

NICHOLAS J. BOHN. 15
